United States Patent Office.

JOHN MATHEIS, OF OTTAWA, ILLINOIS.

Letters Patent No. 80,081, dated July 21, 1868.

IMPROVED MACHINE FOR PUNCHING LEATHER STRAPS FOR FLY-NETS.

The Schedule referred to in these Letters Patent and making part of the same.

TO ALL WHOM IT MAY CONCERN:

Be it known that I, JOHN MATHEIS, of Ottawa, in the county of La Salle, in the State of Illinois, have invented a new and improved Machine for Punching Leather Straps for Fly-Nets; and I do hereby declare that the following is a full and exact description thereof, reference being had to the accompanying drawings, and to the letters of reference marked thereon.

The nature of my invention consists in constructing a machine for punching series of holes in leather straps, the operation being done by means of turning a crank, the machine also doing its own feeding, and is adapted for punching either wide or narrow straps.

The machine is also provided with a simple and efficient device for regulating the distance between the holes. To enable others skilled in the arts to make and use my invention, I will proceed to describe its construction and operation.

Figure 1 in the drawings is a vertical plan.

Figure 2 is also a vertical plan.

Figure 3 is a vertical section through *a b*, fig. 1.

The lines in red exhibit the motions and the extent of the motions of the movable parts. I construct a frame, A, of cast iron, in two parts, the parts being connected at the bottom by means of the connecting-bars, B B. A shaft, C, having bearings on both parts of the frame, A, passes through said frame, having on it a pulley, D, of cast iron, which pulley is covered by a hoop or rim of sheet brass, E. Through the top of the frame A passes the crank-shaft F, having on one side a balance-wheel, G, on the other end a crank, H, and in the centre the shaft itself is bent to form the crank I. To the crank I is attached the pitman J. This pitman is made of two heads, J¹ and J², the one having a right-hand and the other a left-hand thread. These screw into a long-nut or sleeve, K, in such a manner that, by turning the nut or sleeve K, the pitman J can be made longer or shorter. To the head J² is attached the rod L, which has at its lower end a flange, into which are fastened the hollow punches M M. It will be seen that, by turning the crank-shaft F, the rod L will receive through the pitman J a reciprocating motion, its downward motion being exactly to the point where the hollow punches M M touch the brass rim E. The brass rim E has attached, at one point of its circumference, a steel hook, N, into which is hooked the strap to be punched.

At the outer end of the shaft C is keyed a ratchet-wheel, O, which is driven by a pawl, P, through the lever Q, the rod R, and the crank H, in such a manner that, for every turn of the crank-shaft F, the ratchet-wheel O, and consequently the pulley D, are driven a certain distance, to be regulated by the disposition of a series of holes, y y y, in the lever Q, in such a manner that the pawl P will take hold of a greater or less number of the teeth of the ratchet-wheel O. In order to prevent the wheel O from turning backwards, a second pawl, S, is adapted, in connection with an eccentric, T, by means of which the pawl S can be set in just the proper position to retain the wheel O in the identical place to which it has been carried by each successive movement of the pawl P.

The cross-bar U serves as a guide to the rod L, and has also attached to it the elastic guide V, which presses down on the strap to be punched. To accommodate itself to different widths of straps, the guide V has a bolt, W, through it, by means of which the guide V can be made wide or narrow, it being made elastic enough to give or compress as much as is required. To operate the machine, it is necessary to first punch a hole by hand in the strap, after which it is hooked to the hook N, and, after bringing it under the punches M M, it is only necessary to turn the balance-wheel G, when, for each of its revolutions, a pair of holes will be punched in the strap.

When it is desired to change the gauge or distance between the punches M M, the rod L is removed by disconnecting it from the pitman J, and another of a different gauge is inserted in its place.

What I claim as my invention, and desire to secure by Letters Patent, is—

1. The pulley D, the brass rim E, the hollow punches M M, the rod L, the pitman J, and the crank I, when

combined with each other in a machine for punching straps for fly-nets, and constructed substantially as and for the purpose described in the foregoing specification.

2. The ratchet-wheel O, the pawl P, the lever Q, the rod R, the crank H, the pawl S, and the eccentric, T, when combined with each other in a machine for punching leather straps for fly-nets, substantially as and for the purpose described in the foregoing specification.

3. The elastic guide V, when applied to a machine for punching leather straps for fly-nets, substantially as and for the purpose described.

JOHN MATHEIS.
